COMBINED ROTATING CAFETERIA TYPE FOOD SERVICE COUNTER AND DISPLAY SHELF

Elmer R. Weddendorf, 2541 N. Bend Road, Apt. 4,
Cincinnati, Ohio 45239

Filed Sept. 3, 1974, Ser. No. 502,566

Term of patent 14 years

Int. Cl. D6—04

U.S. Cl. D6—146

FIG. 6

FIG. 7

FIG. 1 is a front elevational view of a first embodiment of a rotating cafeteria type food service counter having an elevated display shelf showing my new design;

FIG. 2 is a rear elevational view of the first embodiment shown in FIG. 1;

FIG. 3 is a top plan view of the first embodiment shown in FIG. 1, and of the second embodiment shown in FIG. 5, with some of the projecting elements shown broken away for convenience of illustration;

FIG. 4 is a cross-sectional top plan view of the first embodiment shown in FIG. 1 taken along line 4-4 of FIG. 1 showing the rotating counter surface adapted for buffet style service;

FIG. 5 is a front elevational view of a second embodiment of a rotating cafeteria type food service counter having an elevated display shelf showing my new design;

FIG. 6 is a rear elevational view of the second embodiment shown in FIG. 1; and

FIG. 7 is a cross-sectional top plan view of the second embodiment shown in FIG. 5 taken along line 7-7 of FIG. 5 showing the rotating counter surface adapted for predished food style service.

I claim:

The ornamental design for combined rotating cafeteria type food service counter and display shelf.
